UNITED STATES PATENT OFFICE.

WALLACE W. GASS, OF MAYODAN, NORTH CAROLINA.

BARBER'S REGISTER.

No. 914,265.

Specification of Letters Patent.

Patented March 2, 1909.

Application filed January 16, 1908. Serial No. 411,173.

To all whom it may concern:

Be it known that I, WALLACE W. GASS, a citizen of the United States, residing in Mayodan, in the county of Rockingham and State of North Carolina, have invented certain new and useful Improvements in Barbers' Registers, of which the following is a specification.

The object of my invention is to provide means for keeping a record of the transactions of a barber shop as the work progresses which shall indicate at all times, both to the barbers and to the customers, the total of the number of pieces of work done and waiting to be done, and separately, the number of unfinished pieces of work ahead entitled to service, the mechanism being so organized that when a customer enters the shop he may, at a glance, see how long he will be required to wait and then by depositing an appropriate coin and pushing a button he may receive a ticket bearing his turn number, and at the same time, cause devices to be operated which shift the registering and indicating mechanism to cause them to show his number, which, when called, will entitle him to immediate service, and in which the mechanism is provided with devices by means of which the barber, when he completes a piece of work, may so shift the indicating mechanism that it will show the number of pieces of work completed, and the number of customers whose work is uncompleted or are waiting.

In carrying out my invention, I provide within a suitable casing three sets of registering and indicating wheels, ticket printing and feeding mechanism, coin chutes, and actuating devices so constructed and arranged that the customer cannot receive a ticket entitling him to the desired service until he has deposited an appropriate coin which operates mechanism which actuates the registering and indicating mechanism to show his turn and to indicate to the next customer entering the shop the number of pieces of work ahead of him.

The coin deposited by the customers is received in an appropriate compartment in a drawer at the bottom of the casing, which drawer also contains compartments for tickets which are deposited by the several barbers as soon as they are received or after the work is completed, each barber having assigned to him a compartment in the drawer

which may be under lock and key so that at the end of the day's work, the number of pieces of work done by each barber may be easily ascertained.

Other features of my invention and the details of construction will be hereinafter more fully described.

In the accompanying drawings, Figure 1 is a perspective view of a barber's register constructed in accordance with my invention. Fig. 2 is a detail view showing part of the registering and indicating mechanism. Fig. 3 shows a further detail of this mechanism. Fig. 4 is a detail view in section of part of the registering and indicating mechanism. Fig. 5 shows a vertical section on the line 5—5 of Fig. 6. Fig. 6 shows a vertical section with some of the parts broken away on the line 6—6 of Fig. 5. Fig. 7 shows a vertical section on the line 7—7 of Fig. 6. Fig. 8 is a plan view of a portion of the strip of tickets employed. Fig. 9 is a detail view of part of the mechanism which receives the coin and deposits it in the coin chutes. Fig. 10 is a perspective view of part of the mechanism for operating the ticket-feeding and printing devices. Fig. 11 is a perspective view of another part of this mechanism. Fig. 12 is a detail view in perspective of part of the ticket-feeding mechanism; and Fig. 13 is another view of the mechanism shown in Fig. 12.

The mechanism may be arranged within any suitable casing A. As shown this casing is of a general rectangular form being closed at the back, opposite sides, and provided with a removable front piece, A'. At the bottom the casing connects with a drawer casing A² in which slides the drawer A³. The front piece A' may be locked to the other portion of the casing at a. The drawer A³ is provided with a compartment A⁴ to receive the coin and with compartments A⁵ for the tickets. Each of the compartments may be provided with a hinged top A⁶ which may be provided with any suitable locking device. The drawer casing is provided with slots A⁷, shown in Fig. 1, registering with slots A⁸ in the tops A⁶, so that the tickets may be deposited within the compartments A⁵ without opening the drawer A³. Any suitable number of compartments A⁵ may be provided so that each barber may be assigned a ticket compartment in the drawer and he may deposit his tickets therein without opening

the drawer and as he may be provided with his own key, others cannot interfere with the tickets until the close of the day's business. In this way a barber working on commission 5 can keep a separate record of the amount of work that he has done.

Within the casing is arranged three sets of registering and indicating wheels, C, D, and E which show through suitable openings 10 in the front plate A'. The top set of wheels C is for the purpose of indicating the total number of customers or pieces of work registered, that is to say, the number of pieces of work completed plus the number of 15 customers in the chair plus the number of customers waiting to be served and entitled to service. The registering and indicating wheels D are for the purpose of indicating the number of pieces of unfinished work 20 ahead, that is to say, the number of customers in the chair plus the number of customers waiting and possessing tickets entitling them to service. The wheels E are for the purpose of indicating the exact number 25 of customers who have been served, that is, those whose work has been completed. Each of the wheels C has ten numbers displayed on its periphery in regular order from 0 to 9. Each of the wheels has ten corresponding teeth, as indicated in Fig. 5, and 30 each of the wheels is loosely mounted to revolve about a horizontal shaft C', which is mounted to turn in bearing brackets C² attached to the inside of the opposite side 35 pieces of the casing. These bearing brackets are preferably so constructed that the shaft C' may be lifted out from them or replaced readily, and when in position, may be held in place by cotter pins c, as most clearly indicated in Fig. 7. Collars c' attached to the 40 shaft C' prevent sidewise movement of the wheels. Any desired number of wheels may be employed. For convenience I have shown three wheels which together may 45 register from 0 up to 999. These wheels are all free to be turned in one direction, that is downward, as viewed from the front, but are prevented from moving in the opposite direction by means of detent pawls C⁴, which 50 may be of any suitable construction, and which are held in engagement with the teeth of the wheels by spring c⁴, as indicated in Fig. 5, there being a separate detent pawl for each wheel, and each of the detent pawls 55 being pivotally connected with a stationary bracket C⁵ attached to the back of the casing. The right hand or units-wheel C, and also the middle or tens wheel, have secured to, or formed with them, circular plates or disks 60 C⁶, C¹⁰, the peripheries of which are outside the outer ends of the teeth of the wheels, as indicated in Fig. 5, except that each disk is cut away or notched at c⁶ opposite the face of the tooth containing the number 1. These 65 devices are for the purpose of allowing the

carrying or transfer mechanism to operate in the manner hereinafter described. To the rock shaft C' are attached radial arms C⁷ which are connected at their outer ends by a horizontal rod C⁸ on which are pivoted three 70 pawls C⁹, C¹⁰, and C¹¹. The pawl C⁹ is adapted to engage the teeth of the units wheel. The pawl C¹⁰ is arranged to engage the teeth of the middle tens wheel and also the tooth opposite the figure 1 on the disk C⁶ at the 75 proper time. The pawl C¹¹ is adapted to engage the teeth of the hundreds wheel, and also at times, the tooth of the disk C¹⁰ attached to the tens wheel in line with the figure 1 on that wheel. As the shaft C' is rocked, 80 the arms C⁷ and the pawl-carrying rod C⁸ are also rocked. If all of the wheels show zero, then all of the pawls will rest on the wheels in line with the number 1 on each wheel. When the shaft C' is rocked, the pawl C⁹ will 85 operate the units wheel only until it has displayed the numbers from 1 to 9. After this, and on the next movement of the rock shaft, the pawl C¹⁰ will lie in the notch or recess c⁶ of the disk C⁶ and will therefore engage the 90 teeth of the units wheel and the tens wheel so that on the next forward movement both of these wheels will be turned, the number 1 in the tens wheel will be displayed and the 0 of the units wheel will come to view. On the 95 next movement of the pawl-carrying frame, the pawl C¹⁰ will withdraw from the notch c⁶ and will ride on the periphery of the disk C⁶, so that the units wheel will only be turned until the notch c⁶ comes around again, and 100 then the tens wheel will be operated. In like manner the hundreds wheel is properly operated by its pawl C¹¹. An arm C¹⁷ attached to the pawl C¹¹ extends over the pawl C¹⁰, so that when the pawl C¹⁰ is held up by 105 the disk C⁶, the pawl C¹¹ will also be held in an elevated position.

The rock shaft C' carries an arm F which is connected by a vertical rod F' with an arm F² projecting from a horizontal shaft F³, 110 which also carries an arm F⁴ projecting downwardly into the path of coin deposited in the machine and moved against the arm in a manner hereinafter described. The arm F² is normally drawn down by a spring F¹⁰. 115

In the front plate of the machine are coin slots G, G'. For convenience I have designated these slots quarters and dimes, but any suitable number of slots may be provided to receive coins of different denominations. These slots connect with chutes G² which lead downwardly to a coin carrying table H which is reciprocated back and forth beneath the chutes G² in suitable guides. The coin table is provided with a seat h for 120 quarters and a seat h' for dimes, and it is reciprocated by means of a push rod H' carrying at the front a push button H'. The table is pushed normally forward by means of springs H³ on rods H⁴ which are 125 130

guided in a stationary bracket H^5 attached to the back of the casing. By reference to Fig. 6, it will be observed that the bottoms of the seats h , h' are inclined outwardly so that at the proper time the coins may roll from the table into the receiving chutes. They are prevented from rolling out prematurely by the guide plates H^6 on opposite sides of the table. The receiving chutes H^7 , 5 on opposite sides of the table, connect with a single chute H^8 which leads to the compartment A^4 of the drawer. The chutes H^7 have side openings h^7 which permit the coins to roll from their seats into the chutes 10 H^7 when the table has reached the limit of its backward movement, or has brought the coins into line with these side openings. The lower end of the arm F^4 is arranged in the path of the coin or coins as they are 15 moved backward with the table H , and as this arm is moved rearward, it is made to turn the shaft F^3 and to actuate the rock shaft C' of the registering and indicating wheel C , and at the same time to operate the 20 ticket feed mechanism, which will be next described. The arm F^4 is provided with a head f , as shown most clearly in Fig. 6, which is wide enough to come into the path of either a large or small coin carried by the table. 25

30 The rock shaft F^3 carries a downwardly extending arm I which is connected with a ticket feeding slide I' mounted to reciprocate in guides in a ticket trough I^2 . The tickets I^{10} are printed on a continuous strip 35 which is wound on a reel I^3 mounted to revolve freely about a horizontal shaft I^4 in the lower part of the machine. The strip of tickets extends upwardly from the reel to the rear end of the trough I^2 , and is then led horizontally along the trough beneath the slide I' . 40 Each ticket is punched with an opening i adapted to be engaged by a tooth i' at the front and on the under side of the slide I' . This tooth has a straight vertical front face 45 and an inclined rear face i^2 . The weight of the slide is sufficient to hold it down upon the strip of tickets. As the shaft F^3 is rocked, the slide I' is reciprocated back and forth and made to engage the holes i in the ticket 50 strip successively and to feed the tickets one at a time to a delivery opening i^3 in the front plate of the casing. In order to prevent the ticket strip from moving with too much ease forward and to prevent back movement, I 55 may provide any suitable mechanism, but preferably, I cause the ticket to pass through rollers J , J' , as indicated in Fig. 12. The lower roller J' is provided with ratchet mechanism J^2 which permits it to revolve only in 60 the direction indicated by the arrow, while the upper roller J has spring pressure devices j which press it downward upon the strip of tickets. Obviously by such mechanism the tickets may be fed forward when 65 properly engaged by the ticket-feeding slide

I' , but are prevented from moving backward when the slide is retreating, or for any other reason.

The tickets, as indicated in Fig. 8, are consecutively numbered, and I have provided mechanism by which as each ticket is delivered it is stamped with a number corresponding with the value of the coin deposited. For this purpose I have provided two type-carrying heads K , K' . The type-carrying head K , for instance, carrying the number 10, and the head K' , the number 25, corresponding respectively with a ten-cent piece or a twenty-five cent piece. The head K is carried by an arm K^2 extending 70 forwardly from a rock shaft K^3 supported in brackets L , L' attached to the back of the casing, while the head K' is attached to a rod K^4 attached to the outer end of an arm K^5 on a rock shaft K^6 mounted to turn in 75 the brackets L , L' . The shaft K^3 carries an arm K^7 carrying a horizontally arranged arm K^8 extending through a slot m and in a vertically oscillating lever M' mounted to turn on a rod m' projecting from a bracket 80 m^2 attached to the inner right hand side of the casing. In like manner the rod K^6 carries an arm K^9 provided with a laterally extending arm K^{10} that extends through a slot m^3 in another vertically oscillating lever 85 M^2 on the rod m' . The vertically oscillating levers M' , M^2 are properly spaced as indicated in Fig. 6 and arranged to oscillate independently. Their downward movement is limited by the bracket H^5 . The lever M^2 90 has an inclined lower edge m^4 adapted to be engaged by a coin, in this instance a twenty-five cent piece, while the lever M' is provided with an inclined lower edge m^5 adapted to be engaged by a ten-cent piece. When a coin 95 is dropped through a slot G , or G' it is conveyed by the chute G^2 to the table H , when the latter is in its forward position, shown in Fig. 5, and it seats itself in one of the seats h or h' , in which position it will have a portion overlapping or arranged in front of the head f of the lever F^4 . If now, the button H^2 be pressed inward, it will carry the table 100 rearward and cause the arm F^4 to be rocked, imparting a corresponding movement to the 105 shaft F^3 , and then by means of the arm I , move the feed slide I' . The coin will also come in contact with the inclined surface m^4 or m^5 of the oscillating lever M^2 or M' and will cause the lever to rise at its rear end, 110 115 and, through the mechanism hereinbefore described and as clearly indicated in Figs. 10 and 11, actuate the printing heads K , or K' .

In order to ink the type of the heads K and K' , I provide an ink pad O carried by 120 an arm o pivoted to the slide I' and having a relatively heavy rearward extension o' which is arranged to normally hold the pad O in an elevated position. The part o' is 125 adapted to ride on the upper edge of a guide 130

block Q^2 having a raised portion o^2 , a depressed portion o^3 and a shoulder o^4 . When the slide I' is at the limit of its forward movement, the arm o' is on the lower portion o^3 of its guide and the ink pad is elevated, but when the slide recedes, the arm o' passes up to the elevated portion o^2 of the guide and the ink pad is depressed. The type heads are both held upward by springs f^2 on the rods K^3 and K^6 , as illustrated in Figs. 10 and 11. When the button H^2 is pressed inward therefore, the slide I' is made to recede and about the same time one of the printing heads is made to descend and print the appropriate number on the front ticket in the series. As soon as the customer releases the button H^2 , the feed slide moves forward and causes the printed ticket to protrude through the delivery slot i^3 and the customer can then detach his ticket, which will indicate his turn and will also show the value of the service to which he is entitled. For instance, if he has deposited 25 cents, he is entitled to a hair-cut; if he has deposited 10 cents, he is entitled to a shave and either the number 25 or 10 will be indicated on his ticket. In the act of printing and feeding the ticket, the customer, by rocking the shaft F^3 , has also caused the shaft C' to rock and a unit added to the indicating wheels C , these wheels then showing the number of pieces of work done, the number in the chair, and the number having received tickets and entitled to service including the last customer who has received a ticket.

The wheels D , as before stated, are for the purpose of indicating the number of customers to be served, that is, those in the chairs and those having received tickets and awaiting service. These wheels are mounted loosely on the shaft F^3 , so that the shaft F^3 may be rocked without turning the wheels, while the wheels may be revolved on the shaft without turning the latter. Suitable collars d are provided for preventing sidewise movement of the wheels. These wheels are similar in construction and operation to the wheels C with the exceptions hereinafter noted. A disk D' is secured to the units wheel, this disk being similar to the disk C^6 , shown in Fig. 5, and operating in the same way. An arm D^{10} on the pawl D^7 extends over the pawl D^6 and operates similarly to the arm C^{17} . Detent pawls D^3 are provided for preventing the wheels D from moving in one direction. These pawls are normally held in engagement with the wheels D , by springs d^3 . From the shaft D^3 extend radially upwards and rearwards arms D^4 connected at their upper or outer ends by a rod D^6 carrying the feed pawls D^6 , D^7 engaging respectively the units and tens wheels. As the shaft F^3 is rocked, the wheels D are made to show consecutive numbers

properly and in substantially the same manner as that described in connection with the wheels C above them. The wheels D , however, coöperate with the wheels E in a peculiar and novel manner as will now be described.

The wheels E are mounted to turn on the shaft I^4 mounted in open bearings in the lower portion of the frame. Sidewise movement of the wheels is prevented by the collars e , and detent pawls E^{10} prevent back movement of the wheels. A disk E^2 , similar to the disk C^6 , is attached to the units wheel and operated in the same way. The feed pawls E^3 , E^4 are carried by a rod E^5 attached to arms E^6 secured to and radiating from the shaft I^4 . The shaft I^4 is oscillated by a lever P having a push button p and an arm p' secured to the shaft I^4 . This lever also has an arm E^7 connected with a spring E^8 attached to a bracket E^9 projecting from the frame by means of which the button p is held in an elevated position. As the button p is depressed the shaft I^4 is rocked and the pawls E^3 and E^4 are correspondingly moved. As long as the pawl E^4 rests on the outer periphery of the disk E^2 , the tens wheel is, of course, not operated, but this comes into operation at the proper time. As before stated, the wheels D and E coöperate with each other in a peculiar way, and therefore before further describing the operation of the wheels E , I will further describe the operation of the wheels D .

As more clearly shown in Fig. 4, the tens wheel D is rigidly secured to a sleeve D^6 which extends through the units wheel. The units wheel carries a series of ten teeth Q at one side and to the sleeve D^6 is attached a wheel Q' , also carrying a series of ten teeth. The wheel Q' is provided with a disk Q^2 corresponding in form and in operation to the disk C^6 . The pawls R and R' , for operating the wheels Q , Q' , are carried by an arm R^2 projecting from the shaft F^3 but free to move independently of said shaft. These pawls, as shown in Fig. 5, are arranged to operate in a direction opposite to that of the pawls D^6 , D^7 . Rigidly connected with the arm R^2 is an arm R^3 having a hooked end R^4 engaging with the rod E^5 which carries the pawls E^3 , E^4 , the arrangement being such that as the pawls E^3 , E^4 are actuated to move the wheels E forward, the pawls R are actuated to move the wheels D in the opposite direction. But, of course, this cannot be done as long as the actuating pawls D^6 and D^7 and the retaining pawls D^3 are in engagement with the wheels D , and devices are provided for, at the proper time, raising the pawls D^3 , D^6 and D^7 out of engagement with the teeth of the wheels D , and at the same time, throwing the pawls R , R' into engagement with the wheels Q , Q' . The lever S , shown in Fig. 1, is provided with a push button s , extends through a slot in the front of the casing and

it is attached to a rod S' mounted to turn in bearings attached to the opposite side pieces of the case. This lever has an arm S^2 extending rearwardly from the rod S' which 5 is provided at its rear end with a laterally projecting pin s' engaging the under side of a lever T hinged to a bracket t at the back of the casing and extending upwardly and forwardly therefrom in an inclined direction. 10 To the upper front end of this lever is connected a spring T' , the lower end of which is attached to the casing at t' . At its rear end the lever T is connected to move with an arm t^2 projecting forwardly and engaging an arm 15 U projecting upwardly from the detent pawls D^3 of the wheels D .

By reference to Fig. 5 it will be observed that when the button s is depressed, the lever T will be raised and the arm t^2 will be 20 correspondingly raised, thus raising the detent pawls D^3 out of engagement with the wheels D . The rod S is provided with a forwardly projecting arm V connected by a link V' with a lever W hinged at w to the 25 back part of the frame and connected by a link X with one of the pawls R, R' as clearly shown in Figs. 5 and 6. It is clear that when the button s is in its elevated position, the pawls R are out of engagement with the 30 wheels Q, Q' , and that at this time the detents D^3 are in engagement with the wheels D . Rigidly connected with the lever T is an arm Y which is operatively connected with a bracket Y' extending upwardly from 35 one of the feed pawls D^6 , the arrangement being such that when the button s is in an elevated position, the detent pawls D^3 are in operative engagement with the wheels D , and the feed pawls D^6, D^7 are free to operate 40 these wheels, while the pawls R are held out of engagement with the wheels Q, Q' . When thus arranged, whenever a customer deposits a coin and operates the push button H^2 , the several wheels C, D , and E are made to 45 show an increase of one in each unit wheel of the two sets, of wheels C and D but after a barber has completed a piece of work it is desirable that, without interfering with the number indicated by the wheel C , he should 50 increase by one the number indicated by the wheels E , and decrease by one the number indicated by the wheels D . He can readily do this by depressing the button s which will throw out of engagement the actuating pawls D^6, D^7 and the detent pawls D^3 , and throw into engagement the actuating 55 pawls R without disturbing the other mechanism, and then by pushing on the button p , he can move the units wheel E forward one 60 step and move the units wheel D back one step.

In order to prevent the tens wheel D from being accidentally moved, I have provided brake devices, illustrated in Figs. 2 and 3, comprising a spring arm Z attached to the

case and having a tooth z adapted to engage recesses z' in the side of the tens wheel, as clearly indicated in Figs. 2 and 6.

From the foregoing description it will be understood that a complete record of the 70 transactions of a barber shop may be conveniently kept. A customer entering the shop will see at a glance how much work has been completed during the day, or any particular time and how much work must be 75 done before his turn comes. The barber can also observe the progress of the work and as each customer is disposed of, he can so shift the mechanism as to show a decrease in the number of patrons to be served. As each 80 customer receives a ticket plainly printed with his number and with the value of the coin deposited, there can be no dispute as to the time when he is to be served or as to the service to which he is entitled. Payment 85 in advance is insured and when the customer has left the chair he need not be detained to settle for the work. A check is also, in this way, kept on the cash drawer, as the amount in the cash drawer should correspond with 90 the value of the tickets deposited, and as each barber has a separate compartment for the deposit of his tickets, he will know at the end of a day the value of these tickets and the amount of work done, and if he is working on commission, he will have absolute security as he has control of the tickets until 95 the end of the day's work. While on the other hand, he cannot deposit a ticket until it is fed from the machine to a customer who 100 has previously deposited his coin.

I claim as my invention:

1. A barber's register, comprising indicating mechanism for showing the total of the number of pieces of work done and to be 105 done, indicating mechanism showing the number of pieces of work to be done, means for simultaneously operating both sets of indicating mechanisms to correspondingly advance them step by step at each operation, mechanism for showing the number of pieces 110 of work finished, and means for advancing the indicating mechanism for showing the number of pieces of work finished and for simultaneously setting back the indicating 115 mechanism showing the number of pieces of work to be done.

2. A barber's register, comprising indicating mechanism for showing the total of the number of pieces of work done and to be done, 120 indicating mechanism showing the number of pieces of work to be done, ticket feeding mechanism, means for simultaneously operating the ticket feed mechanism and both sets of indicating mechanisms to correspondingly advance them step by step at each operation, mechanism for showing the number of pieces of work finished, and means for advancing the indicating mechanism for showing the number of pieces of work finished 125 130

and for simultaneously setting back the indicating mechanism showing the number of pieces of work to be done.

3. The combination of one set of numbered indicating wheels, advancing devices therefor, another set of numbered indicating wheels, a handle by which they are operated, connections between the advancing devices of the first set of wheels and the handle operated wheels whereby the first set of wheels are made to turn in a direction opposite to that in which they are turned by the mechanism which advances them, and means for at this time withdrawing said first mentioned advancing devices from the first set of wheels.

4. The combination of a set of numbered indicating wheels, means for operating them, another set of numbered indicating wheels, feed pawls for operating them, means for withdrawing these feed pawls, another set of feed pawls arranged to actuate the wheels in a reverse direction connections between said feed pawls and the operating means for the first set of numbered indicating wheels and means for withdrawing these pawls from, or causing them to engage said numbered wheels.

5. A barber's register comprising indicating mechanism for showing the number of pieces of work to be done, indicating mechanism for showing the number of pieces of work finished, ticket feeding mechanism, means for operating simultaneously the mechanism for indicating the number of pieces of work to be done and the ticket feeding mechanism, and other means for operating the mechanism indicating the number of pieces of work finished.

40 6. A barber's register comprising indicating mechanism for showing the number of pieces of work to be done, ticket feeding mechanism, means for simultaneously feeding the tickets and advancing said ticket feeding mechanism, indicating mechanism showing the number of pieces of work finished, and means for simultaneously advancing said last mentioned indicating mechanism and for setting back the indicating mech-

anism showing the number of pieces of work to be done.

7. A barber's register comprising two sets of numbered indicating wheels, means for storing a supply of tickets, means for feeding tickets one at a time, actuating pawls for the two sets of numbered wheels, and means for causing the ticket feed mechanism to operate and for simultaneously actuating the feed pawls of both sets of numbered wheels.

8. A barber's register comprising two sets of numbered indicating wheels, means for storing a supply of tickets, means for feeding tickets one at a time, printing heads for impressing values on the tickets, actuating pawls for the two sets of numbered wheels, and means for causing the ticket feed mechanism and the printing mechanism to operate and for simultaneously actuating the feed pawls of both sets of numbered wheels.

70 9. In a barber's register, the combination of ticket feeding mechanism, two sets of numbered indicating wheels, means for operating one set of wheels in one direction only, and means for operating the other set of wheels in both directions.

75 10. The combination of a set of indicating wheels, detent pawls for checking their movement in one direction, a notched disk attached to the units wheel, a feed pawl for actuating the units wheel, a feed pawl for actuating the tens wheel which overlaps the notched disk, and mechanism for operating said feed pawls.

80 11. The combination of two sets of numbered indicating wheels, a notched disk on the units wheel of each set, feed pawls for operating the units wheel of each set, feed pawls for operating the tens wheel of each set and which overlaps the notched disk, 90 and mechanism for actuating both sets of feed pawls.

In testimony whereof, I have hereunto subscribed my name.

WALLACE W. GASS.
